United States Patent Office

Des. 208,295

Patented Aug. 15, 1967

208,295

STAND-UP TELEPHONE BOOTH

Henry Dreyfuss, South Pasadena, Calif., and Rembert R. Stokes, Indianapolis, Ind., assignors to Bell Telephone Laboratories, Incorporated, Murray Hill, Berkeley Heights, N.J., a corporation of New York

Filed May 31, 1966, Ser. No. 2,489

Term of patent 14 years

(Cl. D13—1)

FIG. 1

FIG. 2

FIG. 3

FIG. 4

FIG. 1 is a front elevational view of our design;
FIG. 2 is a rear elevational view thereof;
FIG. 3 is a top view thereof; and
FIG. 4 is a side view of our design.

The phone is shown in broken lines in FIG. 1 for illustration purposes only.

We claim:

The ornamental design for a stand-up telephone booth, substantially as shown and described.
